UNITED STATES PATENT OFFICE.

GEORGE KAY, FRED WILKINSON, AND ROBERT FISHER, OF JAMESTOWN,
NEW YORK.

ROUNABOUT.

SPECIFICATION forming part of Letters Patent No. 448,241, dated March 17, 1891.

Application filed September 6, 1890. Serial No. 364,209. (No model.)

To all whom it may concern:

Be it known that we, GEORGE KAY, FRED WILKINSON, and ROBERT FISHER, citizens of the United States, residing at Jamestown, in 5 the county of Chautauqua and State of New York, have invented a new and useful Merry-Go-Round, of which the following is a specification.

This invention relates to games and toys, 10 and more especially to that class thereof known as "merry-go-rounds" or "roundabouts;" and the object of the same is to produce certain improvements in machines of this character as heretofore constructed.

15 To this end the invention consists in the specific details hereinafter more fully described and claimed, and as illustrated in the drawings, in which—

Figure 1 is a plan view of this improved 20 merry-go-round, showing two boats, a horse, and a chariot, although it will be understood that these are but four of many similar seats which could be carried by the machine. Fig. 2 is a front elevation of the machine, showing 25 the horse in the foreground and part of the supporting-rim broken away to show the manner in which the horse is caused to move in imitation of cantering. Fig. 3 is a plan, and Fig. 4 an outer end elevation, of the means 30 for rocking one boat. Fig. 5 is a plan, and Fig. 6 a rear elevation, of the means for rocking and rolling the other boat.

Referring to the said drawings, the letter F designates the floor, from which rises an upright U, surrounded by a toothed ring T. Upon this upright is journaled a large frame M, comprising radiating arms and cross-braces, or any other suitable mechanism, and supported at proper intervals by wheels W, 40 which travel upon the floor or upon a track f thereon.

R is a rim carried by the outer ends of the radial arms of the frame M, and in the present instance supported by brackets K a slight 45 distance below said frame, and forming a step by which the players may ascend to the seats. In the outer face of the rim R is preferably formed a groove G, and in this groove travels a belt B, which passes over suitable 50 guide-pulleys g and extends to a source of

power, which may be at a remote point; or the frame M may be driven in any other suitable manner, if preferred.

In Fig. 2 one of the wheels W is shown as provided with a crank C on its shaft or axle, 55 and this crank is connected by a pitman c with the horse's foot, the body of the horse being pivotally mounted, as at V, in a bracket supported on the frame. In this manner the horse will be caused to gallop, and any other 60 seat which was so connected would also be caused to rock.

In Figs. 3 and 4 is shown a different arrangement of devices for causing the same 65 rocking motion of a seat, the latter in the present case being represented as a small boat. A shaft S is journaled in hangers h beneath the frame M, its inner end carrying a gear-wheel O, meshing with the toothed ring T, and its outer end a disk D, having a crank C on 70 its outer face connected by a pitman c with the prow of the boat, and the latter is pivotally mounted in a bracket V upon the frame.

In Figs. 5 and 6 is shown an arrangement of 75 devices causing the same rocking motion, and a rolling motion as well, this motion being in imitation of a motion of a boat at sea. The devices in this case are the same as those last above described, with the following additions: Mounted in a bracket h' beneath the frame is 80 a shaft S', standing at an angle to the shaft S and driven therefrom by intermeshing gears I, and on the other end of this shaft is a disk D', having a crank C', connected with a pitman c'. In this case the bracket V pivotally 85 supports a long yoke Y, which extends beneath the entire length of the boat, and the ends of which are pivotally connected to the bow and stern thereof. The pitman c, leading from the disk D, rocks the boat the same 90 as in the case of the other boat; but the pitman c', leading from the disk D', is connected to the keel of the boat below the upper ends of the yoke and imparts a rolling motion to the boat from side to side simultaneously with its rocking motion in the line of its length. 95

We preferably arrange upon a single frame a number of seats such as above described. The chariot Z will have no motion, except that 100

around the upright. The horse and boat No. 1 will have a rocking motion, and boat No. 2 will have a rocking and rolling motion. In practice we find that a slight rocking motion can be given by connections with one of the wheels W, as shown in the case of the horse; but more violent rocking motions and the rolling motion are best imparted through the toothed ring and the gears meshing there-with, as shown in connection with the boats, the reason being that a horse carries but a single rider and needs but slight movement, whereas the boats are designed for several occupants and offer more resistance to the force which moves them. With a machine of this construction the timid rider can occupy a chariot, one more bold can ride a horse, and others more courageous still can find more vigorous motion in the boats, some of them having a combined rocking and rolling movement, as above described. It will thus be seen that our improved merry-go-round is adapted to people of various ages and desires and of both sexes, and that horses, boats, and chariots are provided for the riders, as well as seats in imitation of other devices which are not here shown or claimed, but which we may use, if desired.

What is claimed as new is—

30 1. In a merry-go-round, the combination, with a rotating frame-work, brackets mounted thereon, yokes pivoted in said brackets, boats pivoted in said yokes at right angles to the pivots of the latter in the brackets, and means,

substantially as described, for imparting a 35 longitudinal rocking motion to said yokes, of a stationary toothed ring, a shaft journaled radially in said frame-work and having a gear engaging said ring, a short shaft connected by gearing with said radial shaft and having 40 a crank, and a pitman connecting said crank with the boat, as and for the purpose set forth.

2. In a merry-go-round, the combination, with the support F and upright U, rising from the same, a toothed ring T, surrounding said 45 upright, a frame M, journaled on the upright, a bracket V, carried by said frame, and a yoke Y, pivoted in said bracket, of a seat mounted in pivots in the yoke at its front and rear ends, a shaft S, journaled in hangers h beneath the frame, a gear-wheel O on its inner end engaging said toothed ring, a crank C on its outer end, a pitman c, connecting said crank with the end of said yoke, the shaft S', journaled in a bracket h' beneath the frame 50 55 and driven from said shaft S by intermeshing gears I, a crank C' on said shaft S', and a pitman c, connecting said said crank with the seat, all as and for the purpose set forth.

In testimony that we claim the foregoing as 60 our own we have hereto affixed our signatures in presence of two witnesses.

GEORGE KAY.
FRED WILKINSON.
ROBERT FISHER.
